No. 895,274.

PATENTED AUG. 4, 1908.

G. E. KELLY & G. F. ROYER.
CONNECTOR FOR RAILWAY CAR BRAKE SYSTEMS.

APPLICATION FILED JULY 18, 1907.

Fig. 1.

Fig. 2.

UNITED STATES PATENT OFFICE.

GEORGE E. KELLY AND GEORGE F. ROYER, OF WILKES-BARRE, PENNSYLVANIA, ASSIGNEES TO KELLY-ARNOLD MANUFACTURING COMPANY, OF WILKES-BARRE, PENNSYLVANIA, A CORPORATION OF PENNSYLVANIA.

CONNECTOR FOR RAILWAY-CAR-BRAKE SYSTEMS.

No. 895,274.

Specification of Letters Patent.

Patented Aug. 4, 1908.

Application filed July 18, 1907. Serial No. 384,469.

To all whom it may concern:

Be it known that we, GEORGE E. KELLY and GEORGE F. ROYER, citizens of the United States, and residents of Wilkes-Barre, in the county of Luzerne and State of Pennsylvania, have invented certain new and useful Improvements in Connectors for Railway-Car-Brake Systems, of which the following is a specification.

10 The present invention relates to improvements in connectors for the pipes or conduits of railway car brake, signal or heating systems, and particularly to devices for such purpose of that character which are adapted 15 to automatically engage similar ones when brought together during the operation of coupling cars.

In the accompanying drawing is illustrated an embodiment of the invention which in 20 general characteristics is similar to that illustrated and described in Patent 811,068 issued January 30, 1906 to George E. Kelly and Jaell M. Arnold, and in the application of said Kelly and George F. Royer, filed February 7, 1907, Serial Number 356,287.

A considerable use on railway cars in actual service of connectors similar to those constructed in accordance with said patent and application has failed to produce any 30 condition under which they will not automatically engage one with another when two cars provided with such connectors are brought into such relation that their draft couplers will interlock. That is the funnel shaped guide of the connector as shown in 35 said patent and application has uniformly engaged the guide pin of the other connector and brought the two connectors into proper engaging relation on curves, and when the 40 two connectors were at different elevations as well as when the cars were coupled on a straight, level track.

Experiments with connectors arranged in 45 relations which have not been met or experienced in the practical use on railways before referred to, however, have shown that under certain conditions, for instance when the connectors are at an abnormally large angle to each other or there is an extreme 50 difference in height, the guide pins will not be properly guided through the funnels as the draft couplers of two cars are engaged, unless there is a modification of the form of pin

and funnel from that illustrated in the patent and application before mentioned. 55

The object of the present invention, therefore, is to provide such a construction of connector of the type referred to as will insure a proper and automatic engagement thereof with another whenever the draft couplers of 60 two cars, provided with the improved connectors, are engaged.

In the accompanying drawing: Figure 1 is a plan view of a connector embodying the present invention and adapted to connect the pipes of the brake, signal and heating systems of a railway train; and Fig. 2 is an end elevation of the connector.

Referring to the drawings, 1 designates the body of the connector which, in the embodiment of the invention illustrated, is provided with three passages controlled respectively by valves 2, 3, 4, and each having one or more internally threaded outlets as at 5, by means of which it may be connected with 75 the pipes or conduits of the brake, signal or heating systems of the railway car.

As the construction and operation of such a connector as is illustrated in the accompanying drawing is described in detail in the 80 patent and application before referred to, it is thought necessary at this time to only describe particularly the improvements or differences between the connector illustrated and those disclosed by said patent and application. 85

The connector is provided with a pin 6 which projects inwardly from the operating face thereof, at one side of the body, being supported by the arm 7 which is riveted or 90 bolted to an ear or bracket extending laterally from the connector body. Surrounding the end of the pin 6 adjacent the arm 7 are a plurality of radially projecting arms 8.

At the opposite side of the connector body 95 is supported the funnel shaped guide 9 which is adapted to receive the pin 6 of another connector when two railway cars provided with the improved connector are coupled together. The guide 9 is substantially circular 100 in cross section like the corresponding element of the connector of the patent and application before referred to, but differs from such earlier device in several particulars. One of the improvements consists in forming 105 a notch 10 in the outer side wall of the guide

adjacent the reduced end thereof which notch communicates with the opening at the reduced end of the guide and provides a substantially elliptical opening at such end.

5 The guide pin 6 is substantially elliptical in cross section and is tapered somewhat adjacent its free end. The outer surface of such tapered section is inclined on a line which is parallel to the line of inclination of the side of 10 the funnel 9 in which the notch 10 is formed. By this arrangement of parts it will be seen that when the guide pin 6 of a connector enters the funnel guide of another connector it will slide freely therein and the parts will 15 not bind even if the connectors are at a very wide angle to each other. If the pin 6 and guide 9 are made in the forms shown in the patent and application referred to, that is, if the pin is cylindrical and of substantially the 20 same width throughout its length and the funnel is provided with a circular opening at its reduced end, it is possible for the pin to bear upon the inner surface of the guide at such angle that the parts will bind and the 25 pin be prevented from passing through the opening at the end of the funnel guide. However, by providing the notch 10 and inclining the outer surface of the tapered section of the guide pin, as shown in the 30 drawing and above described, it is impossible for any such binding to occur and the pin will be uniformly caused to pass freely through the funnel guide and properly position the other parts.

35 Referring to Fig. 2, it will be seen that the enlarged end of the guide 9 is substantially rectangular in form and has a uniform width from top to bottom corresponding to the greatest diameter of said guide. While it is 40 desirable to make the body of the funnel guide substantially circular in cross section, it will be seen that if the forward end thereof is of this form, the full diameter thereof is only available when the connectors to be 45 engaged occupy exactly the same horizontal plane. That is, unless the pin 6 of the one connector is in the same plane as the aperture at the smaller end of the guide it may not 50 properly engage the latter guide. As the cars come together if the guide pin is any considerable distance above or below the central plane of the guide 9 it may imperfectly contact with the latter guide. To 55 avoid this the present invention provides for extending the mouth of the guide 9 so that it has the form of a square parallelogram. That is, by providing four wings 11 at the larger end of the funnel guide 9 the surface with which the pin 6 may contact is uniform 60 throughout the height of the guide 9. Said wings are formed integral with the body of the guide 9 and the inner surface thereof is inclined and forms a continuation of the inner surface of the body of said guide. With 65 this arrangement the guide pin 6 will be

properly adjusted to cause the desired engagement of two connectors which may be at widely varying elevations.

Having thus described the invention, what is claimed and desired to be secured by Letters Patent is:

1. A connector for the pipes of a railway brake system, comprising a body having therein a suitable passage adapted to be connected with a pipe, a guide pin projecting beyond the face of said body at one side thereof and having a body substantially elliptical in cross section, and a funnel shaped guide arranged at the opposite side of said body, substantially as and for the purpose described. 80

2. A connector for the pipes of a railway brake system, comprising a body, having therein a suitable passage adapted to be connected with a pipe, a guide pin projecting beyond the face of said body at one side thereof and a funnel shaped guide at the opposite side of the body, said pin being reduced in width toward its free end and having the outer surface of such tapered section parallel to a surface of the funnel, substantially as and for the purpose described. 95

3. A connector for the pipes of a railway brake system comprising a body, having therein a suitable passage adapted to be connected with a pipe, a guide pin projecting beyond the face of said body at one side thereof, and a funnel shaped guide arranged at the opposite side of said body and having a notch cut in its side and communicating with the aperture at the reduced end thereof, substantially as and for the purpose described. 100

4. A connector for the pipes of a railway brake system comprising a body, having therein a suitable passage adapted to be connected with a pipe, a guide pin projecting beyond the face of said body at one side thereof, and a funnel shaped guide arranged at the opposite side of said body and having its enlarged open end of uniform width throughout its height, substantially as and for the purpose described. 110

5. A connector for the pipes of a railway brake system comprising a body having therein a suitable passage adapted to be connected with a pipe, a guide pin projecting beyond the face of said body at one side thereof, and a funnel shaped guide arranged at the opposite side of said body, the body of said funnel being circular in cross section, and having at its forward end about the circular mouth thereof wings which form a square parallelogram having the diameter of the mouth of the funnel. 120

In testimony whereof we affix our signatures in presence of two witnesses.
